UNITED STATES PATENT OFFICE.

JOHN W. McCORKLE, OF FREEPORT, WASHINGTON TERRITORY.

TUYERE.

SPECIFICATION forming part of Letters Patent No. 236,604, dated January 11, 1881.

Application filed August 10, 1880. (Model.)

To all whom it may concern:

Be it known that I, JOHN W. McCORKLE, of Freeport, in Cowlitz county, Washington Territory, have invented an Improved Tuyere, 5 of which the following is a specification.

The object of the invention is to so construct a tuyere that it will deliver a single straight blast or a blast from a number of points on its circumference radially to the center.

10 Figure 1 of the drawings is a horizontal section, and Fig. 2 a cross-section on line $x x$ of Fig. 1.

B represents the circular casing, C the neck, and a the tapering blast-pipe. a is the straight bore, and $d d$ the curved bores extending 15 around to a stop, f , in line with the blast-pipe.

b represents radial openings, preferably tapered, which lead from the circular parts c of the bores d to the interior. g is a valve in the 20 median bore, and $h h$ valves in the bores on each side. m is a water-inlet orifice connecting with the bores a and $d d$, so as to cool the tuyere when desired.

By this construction a direct single blast is 25 secured when the valve g is open and the

valves $h h$ are closed, and a multiplicity of radial drafts from the periphery to all parts of the fire, or the blast may be confined to one side, according to whether one or both of the valves h are opened when the valve g is 30 closed.

My improved tuyere is made of cast-iron, in two parts, planed to fit together, and cored to form the bores, passages, and openings which have been described. 35

What I claim as new is—

1. The tuyere A B C, having straight blast-passage a and side passages, $c d$, provided with the valves $g h$, the passage g connecting with the interior by radial openings b , as shown 40 and described.

2. The stop f , arranged to form a partition across the bore c , opposite to the blast-pipe, as described, for the purpose specified. 45

3. The water-orifice m , connecting with the bores $a d d$, as and for the purpose specified.

JOHN WILLIAM McCORKLE.
